Patented July 11, 1961

190,864

MICROPHONE

Robert Louis Deschamps, West Chicago, Ill., assignor
to Shure Brothers, Incorporated, Evanston, Ill., a cor-
poration of Illinois

Filed Feb. 29, 1960, Ser. No. 59,547

Term of patent 14 years

(Cl. D26—14)

FIG. 1 is a side elevational view of a microphone showing my new design, the electrical connector being shown in broken lines for illustrative purposes;

FIG. 2 is a top plan view;

FIG. 3 is a fragmentary side elevational view partly in cross-section taken on line 3—3 in FIG. 2, showing one embodiment of my new design;

FIG. 4 is a fragmentary cross-sectional view showing another embodiment of my new design, and

FIG. 5 is a fragmentary cross-sectional view showing still another embodiment of my new design.

I claim:

The ornamental design for a microphone, substantially as shown and described.
